PEBBLE HEATER APPARATUS

Dick S. Hall, Phillips, Tex., assignor to Phillips Petroleum Company, a corporation of Delaware

Application December 28, 1953, Serial No. 400,462

6 Claims. (Cl. 250--223)

This invention relates to pebble heater apparatus. In a more specific aspect, it relates to a means for measuring the pebble circulation rate in a pebble heater apparatus. In another of its more specific aspects, it relates to a method for measuring the pebble circulation rate in a pebble heater apparatus.

In carrying out thermal conversion processes in pebble heater apparatus, a flowing mass of solid heat exchange material, heated to a high temperature by passing gas therethrough in a first direct heat exchange step, is thereafter caused to contact gaseous reactant materials in a second direct heat exchange. The conventional pebble heater apparatus generally comprises two chambers which may be disposed in substantially vertical alignment. The solid heat exchange material is introduced into the upper portion of the first or upper chamber where the material forms a moving bed of solid heat exchange material which flows downwardly through the chamber in direct heat exchange with hot gaseous heat exchange material. In the heat exchange, the solid heat exchange material is heated to a high temperature and then passed to a second or lower chamber in which the hot solid heat exchange material is caused to contact gaseous reactant materials in a second direct heat exchange relation furnishing heat for the treatment or conversion of the gaseous materials. The solid heat exchange material, cooled as a result of the second heat exchange, emerges from the bottom of the second chamber and flows downwardly to the lower part of an elevator which elevates the material to the upper end of a conduit leading into the upper portion of the first chamber.

Solid heat exchange material which is conventionally used in pebble heater apparatus is generally called "pebbles." For a more complete description of the pebbles which can be utilized, reference may be had to U.S. Patent No. 2,536,436.

The pebbles are heated in the upper chamber to a temperature generally in the range of 1400° F. to 3200° F. Ordinarily, pebble inlet temperatures in the lower chamber are about 100° F. to 500° F. below the average combustion gas temperature within the upper chamber. In processes for the production of ethylene from light hydrocarbons such as ethane or propane, the pebble temperatures in the lower reaction chamber are usually in the range of 1200° F. to 1800° F. In the production of acetylene by pyrolysis of hydrocarbons, temperatures in the range of 1800° F. to 3000° F. are desirable. In the practice of such processes, the cracking reaction involved is endothermic requiring for a particular hydrocarbon feed a specific amount of heat to effect the desired depth of cracking. The heat required for this reaction is delivered by the pebbles in the second heat exchange relation previously referred to. It should be apparent that in any given process the rate of flow of pebbles through the lower chamber as well as the temperature of the pebbles is determinative of the amount of heat available for the cracking reaction and the amount of hydrocarbon

2

feed which should be introduced into the reaction chamber. Furthermore, the temperature to which the pebbles are heated in the upper chamber is related to the residence time therein during which the pebbles undergo a first heat exchange with hot combustion gases. In order to operate a pebble heater apparatus so as to obtain the most efficient cracking of the hydrocarbon feed, it becomes important to be able to measure expeditiously the circulation rate of the pebbles through the system.

10 The following objects will be attained by the various aspects of the invention.

It is an object of the present invention to provide a means for measuring the pebble circulation rate in pebble heater apparatus.

Another object is to provide a method for measuring the pebble circulation rate in pebble heater apparatus.

A further object is to provide a means and method whereby the pebble circulation rate in a pebble heater system can be automatically determined.

20 Various other objects, advantages and features of the invention will become apparent from the accompanying disclosure.

In accordance with this invention, in a pebble heater system comprising a pebble heater chamber positioned 25 above a pebble reaction chamber, the lower end of the pebble reaction chamber being connected to the upper end of the pebble heater chamber by a pebble elevating means, a pebble measuring pot is disposed above the pebble heater chamber. The pebble measuring pot is provided with a pebble inlet conduit which is connected to the pebble conduit extending between the upper end of the pebble elevating means and the pebble inlet of the pebble heater chamber. Flow control means are provided whereby the flow of pebbles into the upper end of the pebble heater chamber from the pebble elevating means can be diverted into the pebble measuring pot. By measuring the time interval required to fill the pebble measuring pot of known volume, the pebble circulation rate of the pebble heater system can be readily determined. In

40 a preferred embodiment of the invention, means are provided whereby the pebble circulation rate can be automatically determined. The lower end of the measuring pot is provided with a pebble outlet connected to the upper end portion of the pebble heater chamber, thereby

45 providing means for passing the pebbles into the upper portion of the reaction chamber. By operating in this manner, it is possible at any time during the progress of the particular process being carried on in the pebble heater system to determine the pebble circulation rate

50 through that system.

A more complete understanding of the invention may be obtained by reference to the following description and the drawing in which:

55 Figure 1 is a diagrammatic elevation of the apparatus of the invention, and

Figure 2 is an elevation illustrating a preferred embodiment of the invention.

Referring now to the drawing and in particular to Figure 1, the pebble heater apparatus comprises an upright elongated shell 10 closed at its upper and lower ends by closure members 11 and 12, respectively. Gaseous effluent outlet conduit 13 extends from the upper portion of the pebble heater chamber formed within shell 10 while heating material inlet means 14 is provided in the lower portion of that chamber. Upright elongated shell 16, closed at its upper and lower ends by closure members 17 and 18, respectively, is disposed below shell 10. Pebble conduit means such as conduit 19 or a plurality of such conduits, extending between closure member 12 of shell 10 and closure member 17 of shell 16, connects the pebble heater chamber with the reactor chamber formed within shell 16. Gaseous effluent outlet conduit

21 is disposed in the upper portion of the reactor chamber while gaseous material inlet conduit 22 is provided in the lower portion of that chamber. Pebble outlet conduit 23 extends downwardly from closure member 18 of the reactor chamber, and is connected to the lower end portion of elevator 24. Pebble feeder 26 is provided intermediate the ends of pebble outlet conduit 23 and may be a conventional pebble feeder such as a star valve, a gate valve, a rotatable table feeder, or the like. It is also within the scope of the invention to omit pebble feeder 26 and provide for the control of pebble flow by means associated with elevator 24 as disclosed in the copending application of Lloyd E. Dean, Serial No. 309,252, filed September 12, 1952, now abandoned.

Elevator 24, which is illustrated as being of the gas lift type, comprises engaging pot 27, gas lift conduit 28, and disengaging chamber 29. Lift gas inlet conduit 31 is connected to the lower end of engaging pot 27 while gaseous effluent conduit 32 is provided in the upper end portion of disengaging chamber 29. It is also within the contemplation of the invention to utilize other pebble elevating means such as a bucket type elevator to raise the pebbles from the pebble reaction chamber to the pebble heater chamber.

Pebble conduit 33 containing a flow control means such as gate valve 34 extends from separator chamber 29 to pebble inlet 35. A measuring pot comprising container 36 is disposed above shell 10. As illustrated, container 36 is supported upon closure member 11 of shell 10 by means of upright support members 37. It is within the scope of the invention, however, to provide other means for supporting container 36 above the pebble heater chamber. Pebble inlet conduit 38 extends between pebble conduit 33 and the upper end portion of container 36. As illustrated, conduit 38 is divided into two parts, the upper part containing a flow control means such as a gate or plug valve 39 while the upper end 40 of the lower part is flared. By constructing the pebble inlet conduit in this manner, pebble flow into the measuring pot can be observed and a visual determination made of the time required to fill measuring pot 36 with pebbles. Pebble outlet conduit 41 containing a flow control means 42 extends between the substantially conical bottom closure member 43 of container 36 and closure member 11 of shell 10. A second pebble outlet 44 containing a flow control means 46 is also connected to bottom closure member 43 of container 36. Conduit 44 provides means for removing pebbles from container 36 which it is not desired to return to the pebble heater chamber and can lead to pebble storage facilities or means for weighing pebbles.

Referring to Figure 2, which illustrates a preferred embodiment of the invention, a first source of light 51 is provided in the upper side of pebble measuring pot 36. A first photoelectric cell 52 is positioned opposite source of light 51 and in the direct rays of a beam thrown by that source. Source of light 51 and photoelectric cell 52 are disposed a substantial distance to one side of the vertical axis of the pebble measuring pot so that the pebble stream flowing from inlet conduit 38 will not interrupt the beam of light. A second source of light 53 and a second photoelectric cell 54 are similarly positioned in the lower portion of the pebble measuring pot. Photoelectric cells 52 and 54 are operatively connected to a timer-controller 56 which is adapted to start counting time when the light beam between light source 53 and photoelectric cell 54 is broken and to stop counting time when the light beam between light source 51 and photoelectric cell 52 is broken. The timer can be graduated so as to indicate directly pebble circulation rate in thousands of pounds per hour or other suitable rate. The timer-controller is also operatively connected to valves 34 and 39, and functions to open valve 34 and to close valve 39 when the light beam between light source 51 and photoelectric cell 52 is interrupted.

In the operation of the pebble heater apparatus of Figure 1, pebbles are heated in the pebble heater chamber formed within shell 10 by contact with hot gaseous heat exchange material which may result from the combustion of fuel outside of the heater chamber or in the lower portion of that chamber in a combustion zone separated from the pebble mass, or by burning a fuel in direct contact with the pebble mass within the chamber. Pebbles are introduced into the pebble heater chamber through pebble inlet 35 and form a contiguous gravitating mass which extends downwardly through shell 10, pebble conduit 19, shell 16, and pebble outlet conduit 23 to feeder 26. The pebbles are heated in the pebble heater chamber to a temperature generally in the approximate range of 1400° F. to 3200° F., and thereafter the hot pebbles are gravitated through conduit 19 into the upper portion of the reaction chamber formed within shell 16. Usually pebble inlet temperatures in the reactor are about 100° F. to 500° F. below the average combustion gas temperature within the pebble heater chamber. Gaseous reactant materials introduced into the reaction chamber through inlet conduit 22 contact the gravitating mass of hot pebbles and undergo reaction. The product containing gas is withdrawn through gaseous effluent outlet conduit 21 and thereafter passed to quenching means and a purification system, not shown.

The cooled pebbles flow from the bottom of the reaction chamber through pebble outlet conduit 23 and pass therethrough into engaging pot 27 at a rate dependent upon the operation of the pebble feeder means employed. In the engaging pot, the pebbles contact a stream of lift gas, such as air, which is introduced into the lower end of the engaging pot through lift gas inlet conduit 31. Air is furnished under a pressure and at a rate of flow sufficient to lift the pebbles from the engaging pot to the top of elevator 24. Prior to entry into elevator 24, the air can be passed through a heater in order to raise the air temperature to the approximate temperature of the pebbles, thereby preventing thermal shock. The pebbles are raised by the air stream through gas lift conduit 28 to the top of the elevator where the pebbles fall out of the air stream in disengaging chamber 29 and pass down pebble conduit 33 toward the top of the pebble heater chamber. The air is withdrawn from the separator chamber through gaseous effluent conduit 32.

During the normal operation of the pebble heater system, valve 34 is open while valve 39 is closed, thereby permitting free flow of pebbles into the reaction chamber. When it is desired to measure the pebble circulation rate of the pebble heater system, pebbles leaving disengaging chamber 29 are diverted from their usual passage through pebble conduit 33 and passed into measuring pot 36 by closing valve 34 and simultaneously opening valve 39. The pebbles are allowed to flow into the measuring pot until it is full as observed through the opening in pebble inlet conduit 38 after which flow of pebbles into the heating chamber is resumed by closing valve 39 and opening valve 34. By observing and recording the time interval required to fill the measuring pot of known volume, the amount of pebbles circulating in the pebble heater system can be readily determined. During this operation, valves 42 and 46 in outlet conduits 41 and 44, respectively, are maintained in a closed position. Upon return to normal operation, the pebbles in the pebble measuring pot can be passed directly from the pebble measuring pot into the upper portion of the pebble heating chamber through pebble outlet 41. Conduit 44 provides an alternative means for withdrawing pebbles from the pebble measuring pot and can lead to a weighing means whereby the weight of the pebbles in the measuring pot can be determined. By weighing the amount of pebbles which pass into the measuring pot during a known interval of time, an alternative method is provided for measuring the pebble circulation rate. This latter method of operation also provides a conven-

ient method for calibrating the pebble measuring pot.

When utilizing the apparatus of Figure 2 to measure the pebble circulation rate, pebbles are diverted from their usual passage through pebble conduit 33 and passed into pebble measuring pot 36 by closing valve 34 and simultaneously opening valve 39. Since light sources 51 and 53 and their respective photoelectric cells 52 and 54 are offset from the vertical axis of the measuring pot, the stream of pebbles flowing thereinto does not interrupt the beams of light passing across the measuring pot. As the pebbles build up in the bottom of the measuring pot, the beam of light between light source 53 and photoelectric cell 54 is interrupted, thereby starting the operation of timer-controller 56. As the pebbles continue to fill the measuring pot, the beam of light passing between light source 51 and photoelectric cell 52 is also broken. The operation of the timer-controller is thereby stopped, giving an indication of the time required to fill the measuring pot with pebbles between the two light sources and photoelectric cells. On interruption of the beam of light passing between light source 51 and photoelectric cell 52, the timer-controller also operates to open valve 34 and to close valve 39, thereby permitting the resumption of pebble flow into the reaction chamber. Since the volume of the portion of the measuring pot between the two sources of light and photoelectric cells is a known quantity, the pebble circulation rate can be easily calculated from the measurement of the time required to fill this volume with pebbles as indicated by timer-controller 56. It is to be noted that the top of the pebble bed in the measuring pot assumes a conical shape as pebbles are passed into the pot. Since the conical portion of the pebble bed is substantially uniform in height as it moves upwardly in the measuring pot past the two light sources and photoelectric cells, the time interval as recorded is a correct indication of the time necessary to fill that volume of the measuring pot between the two light sources and photoelectric cells. It is also within the contemplation of the invention to graduate the scale of the timer-controller so that a direct reading of the pebble circulation rate in thousands of pounds per hour is recorded.

It will be apparent that in accordance with the present invention I have provided a simple and positive means and method for determining the circulation rate of pebbles in a pebble heater apparatus. Accordingly, it is possible at any time during the conduct of a process in the pebble heater system to determine if the pebble flow rate is being maintained as required for that particular process. If it is found that the flow rate of pebbles through the pebble heater apparatus is not being correctly maintained, the amount of pebbles entering the pebble elevating means can be varied by adjusting the pebble feeder in the pebble outlet conduit connecting the lower portion of the reaction chamber with the pebble elevating means. In this manner close control over the pebble flow rate is possible, and more efficient operation of the pebble heater apparatus is assured.

As will be evident to those skilled in the art, various modifications of this invention can be made in the light of the foregoing disclosure and discussion without departing from the spirit or scope of the disclosure.

I claim:

1. In a pebble heater system wherein upper and lower closed elongated shells are disposed substantially in vertical alignment with one another and a pebble elevating means has its upper end connected to the upper end portion of said upper shell by a first pebble conduit and its lower end connected to the lower end portion of said lower shell by a second pebble conduit, the improvement which comprises a container disposed above said upper shell; a pebble inlet conduit containing a flow control means and extending from said first pebble conduit to the upper end of said container; a flow control means in said first pebble conduit downstream, with respect to

5 pebble flow, from the junction of said pebble inlet conduit and said first pebble conduit; and a pair of outlet conduits, each containing flow control means, extending from the lower portion of said container, one of said outlet conduits being connected to the upper end of said upper shell.

2. Pebble heater apparatus which comprises, in combination, a first closed, upright, elongated shell; pebble inlet means in the upper end of said first shell; gaseous effluent means in the upper end of said first shell; gaseous material inlet means in the lower end portion of said first shell; a second closed, upright elongated shell disposed below said first shell; pebble conduit means connecting the lower end portion of said first shell to the upper end portion of said second shell; gaseous effluent outlet means in the upper end portion of said second shell; gaseous material inlet means in the lower end portion of said second shell; pebble outlet means in the lower end of said second shell; pebble elevating means having its lower end connected to the lower end of said pebble outlet means; a first pebble conduit extending between the upper end of said pebble elevating means and said pebble inlet means; a container disposed above said first shell; a second pebble conduit containing a flow control means and extending from said first pebble conduit to the upper portion of said container; a flow control means in said first pebble conduit downstream, with respect to pebble flow, from the junction of said first and second pebble conduits; and a pair of pebble outlets each containing flow control means extending from the lower portion of said container, one of said outlets being connected to the upper end of said first shell.

3. The pebble heater apparatus of claim 2 in which a first photoelectric cell is positioned in the upper side of said container in line with an oppositely positioned source of light, the imaginary line connecting said cell and said light source being offset horizontally from the vertical axis of said container; a second photoelectric cell is positioned in the lower side of said container in line with an oppositely positioned source of light, the imaginary line connecting said cell and said light source being offset horizontally from the vertical axis of said container; and a timer operatively connected to said first and second photoelectric cells.

4. A method for measuring pebble circulation rate in pebble heater apparatus, said apparatus comprising an upper and a lower chamber, which comprises gravitating solid heat exchange material as a uniform, contiguous mass through said upper and lower chambers; removing said material from the lower portion of said lower chamber; elevating said material to the upper portion of said upper chamber; diverting the flow of said material from said upper chamber into a pebble measuring chamber; allowing a bed of said material to build up within said measuring chamber, thereby interrupting a first beam of radiation impinging upon a first photoelectric cell, said cell thereupon starting a timer to counting time; continuing to allow said bed to build up within said measuring chamber, thereby interrupting a second beam of radiation impinging upon a second photoelectric cell, said cell thereupon stopping said timer from counting time; terminating the flow of said material into said measuring chamber; and allowing said material to pass into said upper chamber.

5. An improved method of operating pebble heater apparatus which comprises heating a uniform contiguous mass of pebbles contained in a pebble heater chamber to a temperature in the range of about 1400° F. to 3200° F.; gravitating the heated pebbles from the lower portion of said pebble heater chamber into the upper portion of a pebble reaction chamber; contacting said heated pebbles with reactant materials; removing effluent material from the upper portion of said reaction chamber; gravitating cooled pebbles from the lower portion of said reaction chamber into the lower portion of a pebble ele-

vating means; raising said pebbles to the top of said elevating means; passing said pebbles from said elevating means into the upper portion of said pebble heater chamber; diverting the flow of pebbles from said elevating means into a container of known volume for a predetermined period of time, thereby measuring the rate of pebble flow through said pebble heater apparatus; terminating the flow of pebbles into said container and allowing same to pass into the upper portion of said pebble heater chamber; passing the pebbles from said container into the upper portion of said pebble heater chamber; and varying the flow of pebbles from said reaction chamber into the lower portion of said pebble elevating means in accordance with the measurement of the rate of pebble flow through the pebble heater apparatus.

6. The apparatus of claim 1 in which the pebble inlet conduit of said closed container is divided into two portions, the upper portion of said conduit containing said flow control means and the upper end of the lower portion of said conduit being flared.
